BELT FEED LEVER FOR FIREARMS

Douglas V. Schnepel, Pedro Miquel, Canal Zone,
PanamaOriginal application December 11, 1945, Serial No.
634,326. Divided and this application October
17, 1951, Serial No. 251,805

2 Claims. (Cl. 89—33)

(Granted under Title 35, U. S. Code (1952),
sec. 266)

1

The invention described herein may be manufactured and used by or for the Government for governmental purposes without the payment of any royalty thereon.

This invention relates to a belt feed lever for firearms of the automatic type.

This application is a division of my application for Machine Gun, Serial No. 634,326, filed December 11, 1945 and now matured into U. S. Patent No. 2,594,354.

It is an object of this invention to provide an improved belt feed lever for firearms of the automatic type which is of simplified construction and positive in operation.

The specific nature of the invention as well as other objects and advantages thereof will clearly appear from a description of a preferred embodiment as shown in the accompanying drawings in which:

Fig. 1 is a side elevational view of a firearm embodying this invention shown partly broken away to illustrate the belt feed lever.

Fig. 2 is a top view of Fig. 1 with the top of the cover broken away to show the belt feed lever cam and belt feed lever.

Fig. 3 is a side elevational view of the belt feed lever shown in enlarged detail.

Fig. 4 is an enlarged fragmentary detail cross sectional view taken along the line 4—4 of Fig. 2.

Fig. 5 is a perspective view of the belt feed lever.

Fig. 6 is a perspective view showing the relationship between the belt feed lever and a belt of cartridges at the moment the front end of the lever is entering between the leading cartridge and the one adjacent thereto.

Fig. 7 is a perspective view similar to Fig. 6 but taken at the conclusion of counter-recoil movement of the bolt.

The belt feed lever of this invention is pivotally mounted on top of a firearm bolt and is provided with a forwardly disposed knife-like blade end. Such end cooperates with a cam provided on the cover of the firearm to provide a sideways motion to the belt feed lever as the bolt travels forwardly on the counter-recoil stroke. The knife-like end of the belt feed lever enters between the leading cartridge and the one adjacent thereto and as the bolt moves into battery position the belt of cartridges is moved sideways through the cooperation of the cover cam with the belt feed lever to advance the leading cartridge into position to be extracted from the belt on the recoil stroke of the firearm bolt.

There is shown in Fig. 1 a firearm embodying

this invention. Such firearm comprises mainly a receiver 10 in which there is slidably mounted a bolt 11 for longitudinal reciprocating movement. A barrel jacket 12 is secured to the front end of receiver 10 in suitable fashion and supports a barrel 13. A back plate 14 containing a suitable buffer mechanism (not shown) closes the rear end of receiver 10. The top of receiver 10 is closed by a cover 15 hinged to the forward end of receiver 10 by a transverse pin 16. A suitable latch 17 is provided to lock cover 15 in the closed position on receiver 10.

A belt feed lever 18 is pivotally secured near the rear end of bolt 10 by a vertically disposed screw 19. Belt feed lever 18 is a bar shaped member which terminates at the forward end in a knife-like blade portion 20 as shown in Fig. 3. On top of bolt 11 near the left-hand side thereof there is provided a horizontally disposed transverse recess 21. A helical spring 22 is contained within such recess. On the underside of belt feed lever 18 there is secured a vertically disposed pin 23. Pin 23 enters recess 21 and abuts one end of spring 22, such spring therefore biases lever 18 to the left side of bolt 11. Pin 23 limits the sideways movement of lever 18 by contacting the left end of recess 21.

A vertically disposed hole 24 provided in bolt 11 accommodates a locking member 25 which locks bolt 11 to receiver 10 in the battery position of such bolt. A vertically disposed slot 26 provided in the forward end of bolt 11 accommodates an extractor 27 which is pivotally mounted on a transverse pin 28. Extractor 27 is utilized for extracting the leading cartridge from a linked belt 38 of cartridges 39.

Cover 15 is provided with a longitudinally disposed cam 29 which extends substantially the full length of such cover. The forward end of cam 29 is curved inwardly as shown at 30. When cover 15 is in the closed position, spring 22 biases blade 20 of lever 18 against cam 29.

Bolt 11 is unlocked from the locked position by an operating rod 31. Such operating rod is contained within a tubular housing 32 mounted on the side of receiver 10 as shown in Fig. 2 and in a gas cylinder 33. A portion of the gases produced by discharge of a cartridge are admitted through a gas port (not shown) in barrel 13 to gas cylinder 33 through a gas tube 34 and a bracket (not shown) which surrounds barrel jacket 12.

Connection is made between operating rod 31 and bolt lock 25 in a suitable manner so that bolt lock 25 can be unlocked from receiver 10

at the proper moment after discharge of a cartridge to unlock bolt 11 from receiver 10. The means for locking the bolt to the receiver and the means for unlocking such bolt form no part of this invention and hence need not be further described here in greater detail.

Receiver 10 is provided with a transverse feedway 40 and a conventional spring-biased belt holding pawl 41 pivotally mounted adjacent the entrance to feedway 40. Pawl 41 is arranged to be depressed by each of cartridges 39 which pass thereover and then spring up behind such cartridge to hold the entire belt 38 against retrograde movement.

With cover 15 in the closed position as shown in Fig. 1, bolt 11 may be manually retracted by an operating handle 36 provided on operating rod 31 whereupon the leading cartridge 39 is extracted from belt 38 and on the return of bolt 11 to battery position is inserted into barrel 13. Upon discharge of the chambered cartridge, bolt 11 recoils after being unlocked by the operating rod 31 until it contacts the buffer mechanism contained in back plate 14, whereupon suitable driving springs (not shown) return the bolt to the battery position. On the counter-recoil stroke of the bolt, the blade portion 20 of belt feed lever 18 rides along the longitudinal portion of cam 29 and enters between the leading cartridge 39 and the one adjacent thereto at a slightly higher elevation than the central axes of such cartridges. When blade 20 has moved forwardly beyond the rear edges of the links surrounding these two cartridges, the curved portion 36 of cam 29 acts upon front edge of blade 20 and thereby moves the entire belt 38 in the feeding direction along feedway 40. Thus as bolt 11 goes into battery position on the counter-recoil stroke, the belt of cartridges is fed over the proper amount whereby extractor 27 will be in position to extract the leading cartridge from the cartridge belt. Discharge of the cartridge which had been chambered in the barrel on the counter-recoil movement of the bolt repeats the cycle as above described. Belt feed pawl 41 serves to prevent movement of cartridge belt 38 out of feedway 40 as belt feed lever 18 contacts the side of the foremost cartridge 39 during recoil movement of bolt 11.

From the foregoing description it is clearly apparent to those skilled in the art that there is here provided a belt feed lever of simplified design which eliminates the usual transverse reciprocating cartridge feed slide. Furthermore, this belt feed lever is actuated by a simple and readily manufacturable cam contained in the cover of the receiver. The action of this belt feed lever is positive and unfailing in its ability to transfer the cartridge belt across the feedway of the firearm receiver.

I claim:

1. In an automatic firearm having a receiver, a bolt slidably mounted in the receiver for reciprocal movement, a feedway transversely disposed in the receiver and adapted to receive a linked belt of cartridges, a cover removably secured to the receiver to overlie said bolt and

said feedway, a longitudinal cam depending from the underside of said cover and terminating in an inwardly curved portion at the front end thereof, a unitary belt feed lever pivotally secured at the rear end thereof to the rear top portion of said bolt for movement in the plane of the feedway, said bolt having a transverse slot in the top thereof, a spring seated in said slot, and a stud projecting from the underside of said belt feed lever for entry into said bolt slot in abutting relation with the outer end of said spring whereby said belt feed lever is normally urged into contact with said cam, all arranged and constructed whereby said belt feed lever is maintained parallel to the longitudinal axes of the cartridges during the counter-recoil movement of said bolt so as to pass between the leading cartridge and the one adjacent thereto until the front end of said belt feed lever contacts said inwardly curved portion of said cam and is pivoted thereby to move the belt of cartridges transversely across said feedway in the feeding direction.

2. In an automatic firearm having a receiver, a bolt slidably mounted in the receiver for reciprocal movement, a feedway transversely disposed in the receiver and adapted to support a linked belt of cartridges, a cover pivotally secured to the receiver to overlie said bolt and said feedway, a unitary belt feed lever pivotally secured at the rear end thereof to the rear top portion of said bolt, said belt feed lever having a knife-like forward portion for entering between the leading cartridge and the one adjacent thereto at a level slightly higher than the central axes thereof, a longitudinal cam depending from the underside of said cover and terminating in an inwardly curved portion at the front end thereof, spring means continually urging said belt feed lever into contact with said cam to lie substantially parallel to the longitudinal axes of the cartridges lying on said feedway, said inwardly curving portion of said cam being positioned to contact the front edge of said belt feed lever during the conclusion of counter-recoil movement of said bolt whereby said belt feed lever is pivoted in the plane of said feedway to move the belt therealong in the feeding direction for a distance substantially equivalent to the pitch distance between adjacent cartridges, and means for holding said belt against movement in the opposite direction on said feedway as said bolt recoils, said spring means being arranged to return said belt feed lever into contact with the longitudinal portion of said cam after having been withdrawn beyond the rear end of the leading cartridge in said feedway to thereby align said lever for the belt feeding movement of the following cycle of operation.
